ANNUNCIATOR

Randall E. Baker, Needham, Mass., assignor to
 The Holtzer-Cabot Electric Company, Roxbury,
 Mass., a corporation of Massachusetts

Application March 20, 1931, Serial No. 524,070

3 Claims. (Cl. 177—326)

The present invention relates to annunciators.

The object of the present invention is to provide a simple and compact multi-signal annunciator capable of being viewed from either side.

5 To this end, the present invention comprises the annunciator hereinafter described and particularly defined in the claims.

In the accompanying drawings showing the preferred form of the invention, Fig. 1 is a front elevation of one side of the preferred form 10 of annunciator; Fig. 2 is a view of the annunciator shown in Fig. 1 with the cover removed; and Fig. 3 is a section on line 3—3 of Fig. 1.

The illustrated embodiment of the invention 15 comprises a hollow rectangular frame 10 having viewing panels 12 and 13 with transparent or translucent numerals or other characters thereon. The casing is attached to a support 14 which is adapted to be secured to a wall in such a manner that the annunciator protrudes 20 into the corridor.

The characters on the panel 12 are arranged in two columns, the odd numerals in the left-hand column, and even numerals in the right-hand column, the two columns being staggered. 25 This arrangement is particularly adapted for a doctor's paging system, wherein any doctor's call consists of a number of two or more digits. In the arrangement of the characters in two 30 columns, it has previously been necessary to employ two separate annunciators for installations where visibility on both sides is necessary. According to the present invention, the characters 35 are visible in the same order on both sides of the annunciator with a smaller number of lamps than would be required in two separate annunciators. The invention accordingly permits the use of common lamps for one column of digits, as viewed from either side of the annunciator, 40 while separate sets of lamps are used for the other columns. Thus the panels on opposite sides of the annunciator are illuminated for the even digits by a single set of lamps, whereas the sets of odd digits are illuminated by separate 45 sets of lamps. Whether viewed from either side, therefore, the numerals 1, 3 and 5, etc. appear at the left of the even numerals 2, 4, 6, etc. In other words, the even digits of both panels are in register and may be illuminated from a single 50 set of lamps, whereas the odd digits are out of register and must be separately illuminated.

The frame is provided internally with two uprights 18 and 20. Secured to the upright 18 is a bank of five closed cubical compartments 22 of less depth than the depth of the frame and

open only to the panel 12 of the annunciator. Similarly to the upright 20 is secured a bank of five closed compartments 24 open only to the panel 13 of the annunciator. Between the compartments 22 and 24 is a bank of five compartments 26, extending completely through the frame and open to both panels of the annunciator. Lamp sockets 28 for the compartments 22 are secured to the upright 18, and sockets 30 for the separate compartments 24 are secured to the upright 20. Sockets 32 for the intermediate compartments 26 are secured to the walls of the cells immediately in back of the bank of cells 24. Each socket is fitted with a lamp, as shown in Figs. 2 and 3.

The frame is provided at both sides with removable doors 32 and 34 which are attached to the frame by screw clamps 36. The door 32 has a flange 38 receiving a gasket 40. The panel 12 on one side of the annunciator is secured between the gasket 40 and a series of resilient blocks 42 which are held in place by metallic clips or brackets 44 welded to the inside of the door. The panel for the other side of the annunciator is similarly held in the door 34. As shown in Fig. 3, each panel preferably comprises two sheets of glass 46 and 48 between which is held a photographic film on which the characters appear. The film is opaque except for the transparent or translucent areas of the characters themselves. The characters are practically invisible against the dark interior of the compartments until the lamps are illuminated. For either panel, the even numbered characters appear over the middle compartments 26, while the odd numbered characters appear at the left thereof and are illuminated by the lamps in either the compartments 24 or the compartments 22. It will be seen that the panels thus are of identical construction, and may be set up on either side of the annunciator.

The lamps are connected to any suitable call mechanism. The lamps of the middle compartments are separately wired, as indicated by the connection 50 shown in dotted lines for the character 0. The lamps in the cells 22 are wired in parallel to corresponding lamps of the cells 24, as indicated by the dotted lines 52 for the characters 9, so that the showing of any of the odd digits is duplicated on both sides of the annunciator. The wires are run in a cable 54 passing through the support 14. By the present construction, therefore, the same indication is given on both sides of the apparatus, so that the annunciator can be placed in the middle of a long corridor.

ridor where it can be viewed from both sides. The annunciator employs only fifteen lamps as compared with the twenty lamps which would be required for similar indications with two separate 5 annunciators.

Having thus described the invention, what is claimed is:

1. An annunciator comprising a frame, partitions mounted in said frame, dividing said frame 10 into a plurality of compartments arranged in three vertical columns, a viewing panel for each face of said frame, each panel having two vertical columns of characters, one column of characters on each panel being disposed opposite the middle 15 column of compartments and the other column of characters on said panel being disposed opposite one of the other columns of compartments, the columns and characters on both of said panels being similarly disposed as viewed from the front 20 of each panel, a lamp in each compartment, each character being rendered visible when the lamp in its corresponding compartment is energized.

2. An annunciator comprising a frame, partitions mounted in said frame dividing said frame 25 into a middle vertical column of compartments which opens on both faces of said frame, and two vertical columns of compartments on opposite sides of said middle column, the compartments of one of said last mentioned columns opening 30 only on one face of said frame to one side of said middle column as viewed from that face, the compartments of said other last mentioned

column opening only on the opposite face of said frame to the same side of said middle column as viewed from said opposite face, viewing panels mounted on opposite sides of said frame covering said compartments, each panel having two vertical 5 columns of characters, each column of characters being disposed opposite the compartments which open toward it, the arrangement of characters on each panel being similar as viewed from the front of each panel, and a lamp mounted 10 in each compartment, each character being rendered visible when the lamp in its corresponding compartment is illuminated.

3. In an annunciator comprising a frame, partitions mounted in said frame dividing said frame 15 into a plurality of compartments arranged in three vertical columns, viewing panels mounted on opposite faces of said frame to close said compartments, each of said panels being provided with a similar vertical column of characters, each 20 character of said column being disposed opposite a corresponding compartment of the middle column of compartments, a second column of characters on one panel disposed opposite one 25 of the end columns of compartments and a second similar column of characters on the other panel disposed opposite the other end column of compartments, a lamp mounted in each compartment, each lamp when energized rendering its 30 corresponding character on the panels visible.

RANDALL B. BAKER.
